(57) **CLAIM**

The ornamental design for a catalytic sail for a dry hydrogen peroxide (DHP) generating device, as shown and described.

DESCRIPTION

FIG. 1 is a perspective view of catalytic sail for use in a dry hydrogen peroxide (DHP) generating device of the present application.

FIG. 2 is a front view of the catalytic sail of FIG. 1.
FIG. 3 is a back view of the catalytic sail of FIG. 1.
FIG. 4 is a left side view of the catalytic sail of FIG. 1.
FIG. 5 is a right side view of the catalytic sail of FIG. 1.
FIG. 6 is a top view of the catalytic sail of FIG. 1; and,
FIG. 7 is bottom view of the de catalytic sail vice of FIG. 1.
